SHIRT COLLARS

Alvin Rothman, Fresh Meadows, N.Y., assignor to
Phillips-Van Heusen Corporation, New York, N.Y., a
corporation of New York

Filed Dec. 15, 1961, Ser. No. 159,569
1 Claim. (Cl. 2—116)

This invention relates to wearing apparel, and more particularly to outer garments such as shirts, and it has for one of its objects the provision of an improved collar-fastening means.

In shirts intended for both informal wear and formal wear, collar-fastening means of such form is provided that the collar may be worn either sport-shirt fashion or closed for more formal wear, as with a neck-tie. When the collar is worn in open condition, or sport-shirt style, at least one of the fastening elements, and usually a loop, is exposed to view and it serves to detract from the desired clean-cut appearance of the neck area of the garment. It is desirable that means be provided for concealing the loop when the same is not needed for use in closing the collar and the present invention relates to such means.

It is an object of the invention to provide a loop for closing of the collar when required and to provide means by which the loop may be retracted into a pocket for its reception when it is not being used.

More particularly, the invention contemplates the provision of an elastic loop located at the upper edge of the front of the shirt and so attached to the garment that it can be retracted or pushed between layers of the shirt front and thereby concealed from view, yet which will be available for extension when required for use as a fastening element for the front of the collar.

With these and other objects to be hereinafter set forth in view, I have devised the arrangement of parts to be described and more particularly pointed out in the claim appended hereto.

In the accompanying drawing, wherein an illustrative embodiment of the invention is disclosed.

FIG. 1 is a front elevational view of a shirt collar arrangement constructed in accordance with the invention and showing the loop in its extended position;

FIG. 2 is a view of a part of the shirt and collar, with some parts in section to disclose construction;

FIG. 3 shows the shirt collar as it appears when closed, and with one of the collar extremities folded back to disclose the fastening means, and

FIG. 4 is a sectional view, taken substantially on the line 4—4 of FIG. 2, looking in the direction of the arrows, but showing the loop extended rather than retracted as shown in FIG. 2.

Referring to the drawing, *i* indicates generally the body of a shirt, which may be of conventional construction, and which is provided with an attached collar 2. The body of the shirt has its ends overlapping at the front in the known manner and fastened by the usual buttons and button-holes.

In the collar band portion of the shirt is located a button 3 which is adapted to receive a loop 4 to maintain the collar in its closed or fastened position when the shirt is being worn in the more formal manner shown in FIG. 3. When the collar is open and the shirt is being worn in an informal or sport-shirt style shown in FIG.

2

1, the loop is then detached from the button 3 and is caused to disappear or be concealed from view by being accommodated in a pocket arranged between layers of the shirt body fabric.

5 The loop 4 is preferably, but not necessarily, composed of elastic cord and is thus stretchable and is readily engaged around the button 3 to close the collar. It also possesses some slight stiffness so that when it is not needed for the fastening of the collar, it can be readily pushed down into the body of the shirt to locate it between the layers thereof and thus be completely concealed from view as shown in FIG. 2.

In order to enable the loop to be thus concealed and thus housed in the body of the shirt between the layers thereof, the seaming or stitching 9, which incidentally is a concealed stitching and not visible as shown in FIG. 1, is interrupted for a short distance along the upper edge of the lapel portion 8 to provide a mouth 8a through which the loop is passed to completely dispose it between the fabric layers 5 and 6 and thus conceal it from view as shown in FIG. 2. The loop is thus concealed in a pocket between the fabric layers.

20 In order to allow the loop to be extended or projected out of the body of the shirt at the top thereof to the position shown in FIG. 1, the attaching means for the loop must be one which permits the shifting of the loop from its concealed to extended position and vice versa. A movable or "floating" fastening for a movable loop of this character may be obtained in various ways, one of which is shown in FIGS. 2 and 4 wherein it will be noted that the base portion of the loop is attached by stitching or otherwise, as shown at 10, between infolded flap extensions 11 and 12 of the fabric layers 5 and 6. Any other means for permitting an outward, extending movement of the loop can be availed of.

25 From the foregoing, the uses and advantages of the described construction will be apparent. When the shirt is worn informally, as a sport shirt, as shown in FIG. 1, the loop 4 can be withdrawn or pushed into its pocket between the layers of the shirt body and it will thus be concealed from view and both of the lapel parts of the shirt will then be free of any exposed fastening elements. In FIG. 1, the loop is shown in its extended position, but actually when the shirt is worn open as therein illustrated the loop can be concealed as above explained. When it is desired to conceal the loop, it is merely pushed down into the pocket between the layers of the shirt body to the position shown in FIG. 2 where in place as therein indicated, it will be completely hidden from view.

30 40 45 50 When the shirt is to be worn for formal wear, or with a necktie, the loop is extended to the position shown in FIG. 1 and the lapel part 8 is brought over toward the button 3 and the loop then extended around the button. The loop, being elastic or stretchable, will permit expansibility of the collar size and afford comfort to the wearer while retaining the collar in a fastened condition.

Having thus described a single embodiment of the invention, it is obvious that the same is not to be restricted thereto, but is broad enough to cover all structures coming within the scope of the annexed claim.

55 60 65 70 75 80 85 90 95 What I claim is:

A collar fastening for shirts comprising, a shirt body having overlapping front parts, one of said parts being composed of a plurality of overlying fabric layers con-

nected together at one edge by stitching, the stitching being interrupted for a distance along the top edge of said part thereby to permit of the passage of a loop between the layers, the layers having infolded flap extensions, an elastic cord loop, means attaching the cord loop between said infolded flap extensions to permit of longitudinal shifting of the loop and infolded flap extensions to which it is attached, the elastic cord loop being of substantially the same length as the infolded flap extensions so that when the cord loop is fully re- 10 tracted in unstressed condition it is completely hidden between said infolded flap extensions and said cord loop

being extendable to project the loop beyond the top of the shirt body to which it is attached.
